METHOD OF MOLDING PRESTRESSED CONCRETE STRUCTURES

Julian Huddleston, Los Angeles, Calif.

Application January 13, 1948, Serial No. 2,017

5 Claims. (Cl. 25—154)

1

My invention relates to the production of structures from cementitious material reinforced where necessary by high tensile strength members such as iron or steel hoops or bands.

While cementitious materials have satisfactory strength in compression for structural uses, they have little strength in tension, but by the use of steel reinforcing rods to take the tension stresses, a wide variety of structures may be advantageously erected using cementitious materials.

It is a particular object of my invention to provide a method of producing circular tanks of cementitious material having a prestressed wall construction so constructed that the wall will not be under tension at any time.

In present methods of building prestressed tanks of cementitious material, it has not been found possible to evenly distribute the stresses of the steel reinforcing hoops, whereas by my method of construction, the reinforcing hoops are brought individually to a predetermined value of tension which is utilized to set up an evenly distributed inward acting stress in the wall which is permanently retained.

Great numbers of circular metal tanks of large size are used but are expensive to maintain since the metal must be protected against corrosion both by the contained fluid and by the atmosphere. Tanks of reinforced cementitious material construction, on the other hand, require practically no maintenance, but have not hitherto come into wide use since a suitable method of construction to produce tanks competitive in final cost with metal tanks has not previously been provided.

It is, accordingly, a particular object of my invention to provide a circular tank construction utilizing cementitious material which may be rapidly and inexpensively erected and will be as satisfactory in service as a metal tank while costing much less to maintain.

Still further objects and features of my invention will hereinafter appear from the following description taken in conjunction with the accompanying drawings.

In the drawings;

Fig. 1 is a perspective view of a circular liquid containing tank of cementitious material having a suspended roof of similar material, a portion of the wall being broken away to show the arrangement of reinforcing members;

Fig. 2 is a fragmentary section on the line 2—2 of Fig. 1 to an enlarged scale;

Fig. 3 is a fragmentary section on the line 3—3 of Fig. 2;

2

Fig. 4 is a perspective view showing the use of a tool of my invention utilized in the method of my invention;

Fig. 5 is a fragmentary view in side elevation and to a larger scale showing the tool in initial applied position;

Fig. 6 is a view similar to Fig. 5 showing the tool in operative position;

Fig. 7 is a view taken on the line 7—7 of Fig. 5.

In the drawings, the numeral 20 indicates a tank of reinforced cementitious material standing upon a cement floor and wall footing 22 and having a suspended top 24. The construction of the watertight joint of the walls with the floor 10 may be of any satisfactory type such as are known in the art of building cement structures and is, therefore, not thought to require particular description or illustration.

The tank top 24 is provided with the usual 20 inspection manhole with cover 26 and bottom outlet port 28 closed by a bolted down plate.

In order to prevent rain from accumulating in the inwardly and downwardly curved suspended roof, I provide a drain pipe 30 connected to an 25 outlet at the bottom of the roof or top, the outlet being covered by a wire mesh strainer 32.

My improved tank construction involves the following steps after the cement floor and footing has been provided.

30 First, a circular single wall form of the proper diameter and height is set up on the floor with vertical reinforcing mesh 34 spaced radially inward from the form wall. The mesh may be supported from the form by soft iron wires looped around the wire mesh and extended through the form and the outer ends may be twisted around vertically arranged rods 36 or light metal strips which are left to be later covered by a second or outer layer of cement. The rods may serve during the erection of the inner layer 38 of the wall 35 as supports for the forms.

Upwardly and outwardly extending pins 40 are 40 secured to the rods or strips 36 by being welded thereto at intervals in their height for a purpose 45 to be later explained.

The inner surface of wall 38 is then built up, as for instance, by spraying an atomized fine mixture of cementitious material onto the inner face of the form until a predetermined thickness 50 has been built up whereupon the inner portion of the wall is allowed to set sufficiently to permit the next step of the method to be put into operation.

It is to be understood that I do not limit myself to a process of spraying a cementitious mixture on a form to build up the inner portion of

the wall since I may prefer to form the inner portion of the wall by positioning inner and outer forms and pour cement or concrete material between the forms, with or without the use of vertical steel reinforcing rods. If reinforcing rods are not used, pins 40 are driven directly into the inner portion of the wall after removal of the forms.

The second step in my novel method of construction involves placing the inner portion of the wall under a predetermined degree of compression, this object being in part achieved preferably, although not necessarily, by the use of a tensioning tool of my invention.

A series of steel hoops 42 are bent around the exterior surface of the wall, each hoop being located at a predetermined height by the appropriate peripheral series of projecting pins 40. The meeting ends of the hoops are joined together permanently, as for instance, by welding.

The hoops are then caused to exert a predetermined pressure on the wall by tensioning the hoops at a plurality of points by the use of a tool generally indicated at 46, and then inserting a series of steel wedges 44 while the hoops are under stress, between the hoops 42 and the wall at appropriate distances from each other, with the wedges in each series preferably staggered with respect to the wedges in the series above and below. The inner portion of the wall is thus brought into a pre-stressed condition.

The third step of my method of constructing tanks of cementitious material is to build up the outer portion of the wall to completely embed the compression applying members and thus avoid the necessity for otherwise protecting the metal members of the construction. I prefer to build up this wall by the process of spraying atomized fine concrete or cement until the requisite thickness has been obtained because of the greater speed and cheapness of this method.

The forms utilized may be of any suitable construction but that preferred by me comprises sheets of corrugated metal such as galvanized iron used with the corrugations running vertically. This material is flexible so that it may be shaped readily to set up forms for the construction of tanks of various diameters and is largely self supporting, thus reducing the work necessary and amount of material required to build rigid forms. Further, the corrugated sheets can be readily treated to prevent the adherence of concrete or cement thereto and will last indefinitely in service.

The steps so far described complete the formation of a tank with a prestressed wall and in some cases may provide the complete tank if no cover or top is required.

Figs. 4 through 7 illustrate a suitable tool 46 of my invention by the use of which the hoops 42, which are each complete rings, may be readily brought to a predetermined tension. It will be evident that the inward stress exerted on the tank wall may be controlled as desired. Since the outward thrust exerted by the liquid on the wall will be in proportion to its head, the thrust will be more toward the bottom of the tank than toward the top. This variation in stress distribution may be provided for by varying the spacing of the hoops which is the simplest method, or by imparting a progressively greater tension to the hoops toward the bottom of the tank.

The tool 46 is formed as a two part lever, the outer length 46a of the lever being yieldably connected to the inner length 46b of the lever. The

yieldable connection of the inner and outer arms of the lever may be formed by plates 48 and 49 hinged together at one end by a pin 50 and held together by a spring 51 mounted on a pin 52 secured in one plate 49, the spring being placed under compression between a nut 53 threaded on pin 52 and the other plate 48. The tension of the spring 51 may be adjusted by nut 53, the usual lock nut (not shown) being provided to prevent slackening back of nut 51. The inner end of arm 46b is provided with a hoop engaging jaw 54 and is pivoted to a fulcrum piece 56 by pin 58. The fulcrum piece is formed as a foot having spaced supporting flanges 60, 61. The lever is pivoted toward one side of the foot, the adjacent flange 60 of the fulcrum piece being jaw shaped to cooperate with jaw 54 in gripping the hoop 42. Flange 61 carries the thrust of the lever when the tool is in operation.

20 The tool 46 is used by engaging jaws 54 and 60 with a hoop and then bearing down on the lever until plates 48, 49 just begin to separate at the edge opposite to the hinge. The position of the hoop engaging parts while tensioning a hoop is shown in Fig. 6. It will be noted that the lever forms a lever of the third order and is arranged to provide a very large transmission of force to the hoop for a moderate pressure on the handle.

It is, of course, possible to attain the predetermined tension in the hoops by the use of the wedges alone and the use of any convenient tension determining instrument to indicate when the predetermined value of the tension has been reached.

35 Most tanks are required to be covered by and my invention contemplates a suitable cover or roof of cementitious material arranged so that the stresses imposed on the walls are compressive, thus utilizing the inherent strength of the material, and also eliminating the cost of the usual method of constructing the forms.

I claim:

1. A method of forming structures with walls of cementitious material comprising: erecting a form for a wall; erecting said wall; applying a series of endless metal bands around the periphery of the wall; prestressing each band at a plurality of spaced points by applying a predetermined force to the band in a direction normal to the wall; applying blocks between the bands and the wall at each prestressed section of the bands to maintain the preestablished stress of said bands and evenly distribute said stress around the wall; and embedding the prestressed bands and said blocks in a layer of protective material.

2. A method of forming structures with walls of cementitious material comprising: erecting a form for a wall; erecting a cementitious inner wall; arranging a plurality of outwardly projecting pins in spaced parallel series around the periphery of said wall; applying an endless metal band on each peripheral series of projecting pins; prestressing each band at spaced points by applying a predetermined force to the band in a direction normal to the wall; inserting wedges between the bands and said wall at each prestressed point to maintain the predetermined stress evenly distributed around said wall; and embedding the prestressed bands and wedges in a layer of protective material forming an outer wall.

3. A method of forming prestressed cementitious structures consisting of: erection of an internal form of a shape corresponding to that of the desired structure, application of plastic material to the exterior of said form to form an

inner wall of desired thickness, application of metallic reinforcing and tensioning rods circumferentially to the exterior of said inner wall after the material has set, permanently joining the ends of said rods to form vertically spaced endless bands, prestressing each band at a plurality of circumferentially spaced points by applying a predetermined force to the band in a direction normal to the wall, inserting elements between said endless bands and said inner wall at certain of said prestressed points to hold the bands in prestressed condition, and spraying a plastic material on to and for embedding said prestressed bands and said holding elements, so as to maintain said structure compressed against possibility of fracture and collapse occasioned by undue stress from the interior of the structure.

4. A method of forming prestressed cementitious structures consisting of: erection of an internal form of a shape corresponding to that of the desired structure, application of plastic material to the exterior of said form to form an inner wall of desired thickness, application of metallic reinforcing and tensioning rods circumferentially to the exterior of said inner wall after the material has set, permanently joining the ends of said rods to form vertically spaced endless bands, prestressing each band at a plurality of circumferentially spaced points by applying a predetermined force to the band in a direction normal to the wall, inserting elements between said rods and said inner wall at certain of said prestressed points to hold the bands in prestressed condition, and spraying a plastic material on to and for embedding said prestressed bands and said holding elements, so as to maintain said structure compressed against possibility of fracture and collapse occasioned by undue stress from

the interior of the structure, said holding elements being staggered in position to adjacent band positions.

5. A method of forming a tank structure having a substantially cylindrical cementitious wall comprising: erecting a form for the wall; erecting said wall; applying a series of endless metal hoops around the outer periphery of said wall, prestressing each hoop at a plurality of circumferentially spaced points by applying a predetermined force to the hoop in a direction normal to the wall; applying blocks between the hoops and the wall at each prestressed section of the hoop to maintain the preestablished stress of said hoops and evenly distribute said stress around the wall; and embedding the prestressed hoops and said blocks in a layer of protective material.
